TRAIN CONTROL

Filed Jan. 31, 1925

W. K. Howe, Inventor

By Neil C. Preston,
his Attorney

UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

TRAIN CONTROL

Application filed January 31, 1925. Serial No. 6,067.

This invention relates to automatic train control systems for railways, and more particularly to a combination of means which requires the engineer to take appropriate action, which for convenience may be called acknowledgment, at or near each of a plurality of successive stop signals in order to avoid a penalty such as an automatic application of the brakes which requires the train 10 to be brought substantially to a stop.

More specifically, it is proposed in accordance with the present invention, to require the engineer to perform an acknowledging act at successive points or intervals of distance 15 during the travel of the train while running under a stop signal through a danger or occupied block or series of blocks. It is proposed to require the acknowledging act for the first danger signal to be enforced a certain 20 distance from the caution signal, and on those systems where the various blocks are of the same length it is proposed to require the engineer to acknowledge the first danger signal at a point beyond a caution signal which 25 will assure bringing the train to a stop from the speed limit imposed at such point before it reaches the stop signal, and for systems in which the blocks are not the same in length the acknowledging point for the first danger 30 signal is preferably selected so as to satisfy the requirements when approaching the signal at danger at the exit end of the shortest block of the system. In the form of the invention illustrated, acknowledgment of stop 35 signals only is required, but obviously provision for the acknowledgment of caution signals in addition to the acknowledgment of stop signals may be added if desired.

Other objects, purposes and characteristic 40 features of this invention will in part be obvious from the drawings and in part appear as the description thereof progresses.

In describing the invention in detail, reference will be made to the single drawing which 45 illustrates a train control system of the two-position continuous inductive type in a diagrammatic and conventional manner.

Although the present invention is applicable to various types of train control systems, 50 such as intermittent systems of various kinds

and continuous inductive type systems of the three-position or three-condition type, it has been shown applied to a simple form of two-position continuous inductive type of train control system so as to simplify the illustration and the description of the same. 55

Trackway apparatus

In the particular embodiment of the invention illustrated, the trackway has been shown as consisting of rails 1 divided by insulating joints 2 into blocks, of which the block I and the adjacent ends of two other blocks H and J have been illustrated. Since all of the various blocks are the same, at least in automatic as distinguished from interlocked train control territory, like parts of each block are designated by like reference characters having distinctive exponents. At the entrance to each block is provided a wayside signal of any of the well known types, and for convenience three-position semaphore signals Z, only have been illustrated, which signals have been shown conventionally without illustrating their operating mechanism or control circuits. 60 Each of these signals assumes the clear position if the block at the entrance to which such signal is located and the next block in advance are unoccupied, assumes a caution position if the next block in advance is occupied and assumes a danger position if the block at the entrance to which it is located is occupied. At the entrance of the block I, the normal direction of traffic being as indicated by the arrow, is located the usual track relay T 65 which under normal clear traffic conditions is energized by the track battery 3¹ connected across the exit end of this block. This battery is connected in series with the secondary winding of the transformer 4¹, this transformer having its primary winding connected to the transmission line 5 through a circuit including the front contact 6¹ of the track relay T¹. 70

From the above description of the trackway apparatus it readily appears that direct current is applied across the exit end of each block at all times so that this direct current may control the direct current track relay at the entrance of such block in accord- 75 80 85 90 95 100

ance with occupancy of the block, and that alternating current is superimposed upon this direct current of a block if the next block in advance thereof is unoccupied. Also, it appears that even though alternating current is applied across the exit end of a block, this current cannot reach a train entering such block if the block is already occupied by another train, this because said another train will shunt this alternating current away from the train in question. In other words, it readily appears that if a train having suitable means for detecting the flow of alternating current flowing down one track rail and back through the other ahead of such train is moving along the track, such train cannot detect alternating current if it enters an occupied block because this alternating current is shunted away by the train ahead, and that such train cannot detect alternating current when entering an unoccupied block when the block next in advance thereof is occupied, because no alternating current is impressed across the rails at the exit end of the block in question due to the fact that the front contact of the track relay of the block ahead is in its retracted position; and therefore alternating current is only detected on the train when the train in question is moving in clear territory.

In the drawing is illustrated a train by the wheels and axles 10, directly in front of the first axle of which are located influence receiving elements each comprising a core 11 having a winding 12 thereon. These windings 12 are connected in series in such a manner that voltages induced therein, due to currents flowing down one rail ahead of the train, through the axles of the train and back through the other rail, are cumulative. The wires leading from these windings 12 are connected to the input leads of a suitable amplifying device A, which device preferably includes suitable sources of energy, tuning devices, filtering devices and amplifying tubes of the vacuum type and which amplifying device has its output leads connected to a main relay MR.

The apparatus thus far described includes the trackway apparatus and the influence receiving apparatus located on a car, and it should be noted at this time that the main relay MR assumes its energized position under normal clear traffic conditions for reasons heretofore given, but that this relay MR assumes its deenergized position if the train travels either in a caution or an occupied block, that is, moves in a block which is occupied or is in a dangerous condition for other reasons, or moves in an unoccupied block when the next block in advance thereof is in danger, and that any change in traffic conditions is immediately manifested by this relay MR regardless of the position of the train in the block.

Car-carried apparatus

Generally speaking, the car-carried apparatus is of the type in which suitable mechanism driven from the wheels of the vehicle is set into operation under predetermined traffic conditions and is similar to that disclosed in a series of patents issued to P. J. Simmen as for example, Patent No. 1,150,308 dated August 17, 1915, and also similar to that disclosed in the application of W. K. Howe, Serial No. 733,975 filed August 25, 1923; so that a detailed illustration and description of the system is not necessary. In systems of the kind mentioned, a speed responsive device (not specifically shown) is located on the train, which device at all times indicates the actual speed at which the train is moving, and the shaft for driving this speed responsive device is at times operatively connected to suitable cam shafts so as to drive these shafts in accordance with the progress of the train along the trackway. In order to simplify the description of the present invention the specific manner in which these cam shafts may be driven by a shaft connected to the axles of the vehicle has not been illustrated, but a high cam starter magnet HCS which governs the clutching engagement of the high to low speed control shaft 16, shown by a dot and dash line, has been shown. This shaft 16 carries a distance cam 17 and a permissive speed cam 18. Similarly, there is provided a speed shaft 19, also illustrated by a dot and dash line, which shaft at all times assumes a position dependent on the actual speed of the vehicle; and this speed shaft controls the speed sector 20 which closes its contacts 69 at a speed below two miles per hour, and the speed arm 21. If desired of course, parts 20 and 69 could be omitted so that an automatic brake application would necessitate bringing the train to a full stop. The speed arm 21 and permissive speed cam 18 through floating lever 22 control the cam-governor contacts 23 through the medium of the sector 24. The speed sector 20, the cam-governor contacts 23, and the distance cam 17 correspond in almost every respect to the speed sector 29, the cam-governor contacts 110 and the distance cam 130 shown in the application of Howe above referred to, so that a detailed description of this mechanism need not be given here. On the train is provided another shaft, conventionally called the acknowledging shaft and illustrated by dot and dash line 25. This shaft normally assumes a biased position by reason of suitable biasing means (not shown) and by means of the energization of the acknowledging cam starter magnet ACS. This shaft 25 is gradually rotated in accordance with the progress of the train if the cam starter magnet ACS is deenergized for the same reason that

shaft 16 is rotated in accordance with the progress of the train if the cam starter magnet HCS is deenergized, these shafts 16 and 25 being governed by cam starter magnets and other mechanism substantially identical in construction. On the acknowledging shaft 25 is contained a signal cam 28, an acknowledging cam 29 and a restoring cam 30, these cams all being keyed to the shaft 25 so as to 10 rotate therewith.

The acknowledging shaft 25 is provided to force the engineer to manifest his vigilance by performing an acknowledging act at repeated distance intervals so long as the train is moving under a stop or danger signal, and to inflict a penalty if the engineer fails to do so when required, and in order to force the engineer to make such repeated acknowledgments the present invention contemplates res-15 to 20 toration and re-initiation of the acknowledging shaft 25 after a distance of travel of said shaft from its normal position.

In order that the acknowledging shaft 25 may be restored to its biased position automatically by means controlled by itself, the restoring cam 30 is provided with switch mechanism of the toggle type. This mechanism, in the particular embodiment illustrated, consists of two switch members 32 and 33 pivoted at 34 and 35 and operatively connected by the link 36. These switch members 32 and 33 assume either of their extreme positions, which are determined by the engagement of rollers 37 and 38 against the curved 30 35 surface of the cam 30, by the action of the toggle spring 39 which spring tends to maintain this toggle mechanism in the last position to which it was operated by the cam portion 70 on the cam 30. This toggle spring 39 is one of the compression type and is contained on the bifurcated guide rod 40 between the shoulder 41 and the washer 42 on this rod, and the bifurcated portion of this guide rod straddles a stationary pin 43, so that the 40 45 spring 39 is compressed for a time as the toggle mechanism is moved from one extreme position to the other.

Since the present invention does not relate to any particular type of brake control mechanism, but relates to train control systems generally which may include brake control mechanism of any desired type, an electro-pneumatic valve EPV has been illustrated for this purpose. This device EPV upon de-50 55 energization may vent the brake pipe directly or may control suitable pneumatically operated brake control mechanism of any desired type.

Before the operation of the car-carried apparatus is taken up in detail, it is considered expedient to trace the normally closed circuits. Under normal clear traffic conditions of the car-carried apparatus illustrated the main relay MR is energized for reasons here-60 65 tofore given. With the relay MR energized

the high cam starter magnet HCS is energized by a circuit beginning at one terminal B of a suitable source of energy, such as a battery, wire 80, front contact 81 of the relay MR, wire 82, winding of the high cam 70 75 starter magnet HCS, wire 83 back to a common return wire C connected to the other terminal of said source of energy.

With the high cam starter magnet HCS energized the permissive speed shaft 16 assumes its normal biased position so that the sector 24 only opens the contacts 23 when the speed of the train is above a maximum of say, 60 miles per hour. With this cam shaft 16 in its normal position, the distance cam 17 allows the contacts 46 to remain closed, thereby maintaining a closed energizing circuit for the acknowledging cam starter magnet ACS which may be traced as follows; beginning from the terminal B, wire 47, contacts 80 85 46, wire 48, winding of the cam starter magnet HCS, wire 49 to the common return wire C.

With the acknowledging cam starter magnet ACS energized the acknowledging cam shaft 25 assumes its normal position, in which it has been illustrated, thereby maintaining a closed energizing circuit for the brake applying device EPV which may be traced as follows:—beginning at the terminal B, wire 62, contacts 63 operated by the cam 28, wire 50, contacts 51, operated by the acknowledging cam 29, wires 52, 53 and 54, cam-governor contacts 23, wire 55, front contact 56 of the device EPV, wires 57 and 58, winding of the device EPV, wire 59 back to common return wire C. It should be noted that the circuit just traced has a branch in multiple with the contacts 63 including the wires 31 and 45 and the normally closed contact 44 of the push button PB. There is still another energizing circuit for the device EPV including the front contact of the main relay MR, traceable from B, contact finger and front contact 26 of MR, wire 27, contacts 23, wire 55, stick contact 56 of EPV, wires 57 and 58, EPV, and wire 59 to C. The functions of these circuits will be pointed out in the operation of the system. With the device EPV energized, the brakes of the vehicle may be controlled by the engineer, and the brakes may be assumed to be released at this time. It may be pointed out at this time that the car-carried apparatus is shown in its normal clear traffic condition with the train moving at a speed above, say, 2 miles per hour and less than 60 miles per hour, so that the contacts controlled by the speed sector 20 are open and the permissive speed or cam-governor contacts 23 are closed.

Operation

As heretofore explained, the main relay MR assumes its energized position if the train is moving in a clear block, but assumes 130

its deenergized position if the train is moving in a caution or danger block, and in this connection it should be remembered that this system is one of the continuous inductive type and that as a block changes either to a more favorable or to a less favorable traffic condition, the main relay immediately manifests such change in traffic conditions, unless this change is from caution to danger or from danger to caution in which case the relay MR remains unchanged.

Let us assume that the train is proceeding along the trackway in a clear block and enters a caution block. As the train enters the caution block the main relay MR assumes its deenergized position thereby deenergizing the high cam starter magnet HCS which in turn initiates the cam shaft 16, so that the permissive speed at which the vehicle may travel is gradually reduced through the medium of a floating lever 22 and the permissive speed cam 18, this permissive speed cam 18 being preferably so shaped that the permissive speed is restricted in accordance with a speed distance braking characteristic for a particular train and so that the speed of the train is restricted to a suitable minimum of say 15 miles per hour at the run-out of this cam. When the high cam shaft 16 has almost reached its ultimate position, the projecting portion of the cam 17 engages the roller 60 thereby causing the contacts 46 to open, and thereby deenergizing the acknowledging cam starter magnet ACS and initiating the acknowledging cam shaft 25.

With the acknowledging cam shaft operatively connected to the wheels of the train by reason of deenergization of this cam starter magnet ACS, the signal cam 28, after a short distance of movement of the train, closes contacts 61, thereby applying energy to the acknowledging signal lamp 62' so that the engineer if alert is informed that he must perform an acknowledging act in order to avoid a penalty, which penalty in the particular arrangement shown consists of an automatic brake application requiring the train to be brought substantially to a stop. Proceeding on the assumption that the engineer is alert and sees the indication signal given by the acknowledging signal lamp 62' he depresses the push button PB and in so doing causes this push button to be held down by the holding magnet 22, this holding magnet being strong enough to hold the push button PB down but being unable to move this push button to its depressed position. With the push button PB in its depressed position a supplemental or auxiliary circuit for the device EPV is closed, which circuit is the same as the one heretofore traced through 62, 63 except that it includes contact 65 of the push button PB and wires 66 and 68 instead of contacts 51 and wire 52. It should be noted that depression of the push

button PB extinguishes the acknowledging signal lamp 62'.

As the train proceeds a little farther into the caution block, the acknowledging cam 29 is rotated to a position to allow the roller 67 to ride into one of the notches of this cam, depending on the direction of movement of the train (pilot or tender leading) thereby opening the contacts 51. It should be noted, that if the engineer had not depressed the push button PB, the device EPV would have been deenergized and an automatic brake application would have been imposed by reason of opening of these contacts 51, but since the push button PB has been depressed and is now held in its depressed position by the holding magnet 22, the device EPV is maintained energized through this auxiliary circuit so long as contacts 51 are open. As the train proceeds a little farther the contacts 51 are again closed after which the contacts 61 are again opened, thereby opening the auxiliary circuit and breaking the energizing circuit for the holding magnet 22, thus allowing the push button PB to return to its normal position. It may be pointed out at this time that the distance moved by the train in a caution block before the contacts 46 are opened, plus the distance moved by the train from the time the acknowledging cam starter magnet is deenergized by the opening of these contacts to the time when contacts 51 open, is such that if the engineer fails to acknowledge the first caution signal the train is sure to be brought to a stop by an automatic brake application before it reaches the signal at danger, it being remembered that the train has been restricted to its minimum speed, of say 15 miles per hour, at the time such acknowledgment is required.

If an automatic brake application is imposed by the opening of the stick circuit for the device EPV for any of the reasons heretofore given, this device EPV remains deenergized until a pick-up circuit for this device EPV is closed. In the arrangement shown, the device EPV is again automatically picked up as soon as the speed has been reduced to say less than 2 miles per hour, as manifested by the closure of contacts 69 governed by the speed sector 20. This pick-up circuit for the device EPV is readily traced in the drawing.

It should be noted that the push button PB has been protected against misuse which might be effected by tying it down or otherwise fastening it so as to place it in its acknowledging position permanently, by providing this push button with a normally closed contact opened when the push button is depressed and included in the energizing circuit of the brake control device EPV. The device EPV does however not depend for its energization on this push button contact except at times when the acknowledging shaft

has almost reached its ultimate position. That is, after a given distance of movement of the train the acknowledging shaft has rotated to a position to cause the contacts 63 to open and under this condition the stick circuit for the EPV depends for its energy on the integrity of the branch circuit in multiple with these contacts 63, namely the normally closed contact 44 of the push button PB. In other words the engineer is required to have the push button in normal position to avoid a brake application a short distance before the acknowledging shaft reaches its ultimate position, so that he is prevented from tying or otherwise fastening this push button in its active position permanently.

The operation of the acknowledging cam shaft 25 has thus far not changed the position of the toggle switch mechanism associated with the restoring cam 30, because the toggle spring 39 maintains this mechanism in the position in which it is placed by the cam 30, and since this cam 30 has not yet been turned far enough to allow the cam portion 70 to engage the roller 38, this toggle switch mechanism still remains in its normal position.

After the train has proceeded along the track with the cam starter magnet HCS energized substantially the distance at which a repeated acknowledgment is required, the cam portion 70 of the restoring cam 30 engages the roller 38 and thereby moves the members 32 and 33 from their normal position, and as soon as these members are moved beyond the mid stroke, the compressed spring 39 completes the movement of the toggle mechanism to the dotted position, so that the contacts 71 and 72 bridge their respective stationary contacts. With this toggle switch mechanism in its dotted position, another auxiliary circuit for the brake control device EPV is closed, which circuit may be traced as follows:—beginning at the battery B, wire 73, contact 71 of the toggle switch mechanism, wires 74 and 54, cam-governor contacts 23, wire 55, stick contact 56 of the EPV, wires 57 and 58, winding of the EPV, wire 59 to the common return wire C.

From the tracing of this circuit, it readily appears that no acknowledgment is required so long as the toggle switch mechanism assumes its abnormal dotted position. Also, with this toggle switch mechanism in its abnormal dotted position, an auxiliary circuit for energizing the acknowledging cam starter magnet ACS is completed, which may be traced as follows:—beginning at the terminal of the battery B, wire 76, contact 72 of the toggle switch mechanism, wires 77 and 48, winding of the cam starter magnet ACS, wire 49 to the common return wire C. With this cam starter magnet ACS energized the acknowledging cam shaft 25, by reason of its bias to its normal position, is returned to the normal

position, in which it is illustrated, and it should be noted that upon its return to normal the momentary opening of acknowledgment enforcing contacts 51 will not effect a brake application, even though no acknowledgment is made just prior to this return of the cam, because the device EPV is energized through the contact 71 of the toggle switch mechanism during the returning cycle of the acknowledging cam shaft 25.

With the toggle switch mechanism returned to normal, the energizing circuit for the cam starter magnet ACS is again broken and the cycle of operation of the acknowledging shaft 25 is repeated, this continuing so long as traffic conditions are dangerous and contact 46 is open. When traffic conditions clear up the cam shaft 16 for well known reasons is restored, contacts 46 are closed and the cam shaft 25 is restored to normal.

We have just considered how the acknowledgment enforcing contacts 51 are shunted by contacts 71 of the toggle switch mechanism upon restoration of the acknowledging shaft by this toggle switch mechanism. Let us now consider conditions when this acknowledging shaft is restored by reason of a change to clear traffic conditions, that is, let us assume that traffic conditions clear up and that the acknowledging shaft is restored by reason of the restoration of the permissive speed cam shaft. Under these conditions no acknowledgment is required in spite of the opening of contacts 51 because the device EPV is now energized by the following circuit closed when the main relay MR is in its energized condition; from terminal B, contact 26 of relay MR, wire 27, cam-governor contacts 23, wire 55, stick contact 56 of EPV, wires 57 and 58, winding of EPV, wire 59 to the common return wire C.

The apparatus described therefore, in addition to requiring the engineer to restrict the speed of the train in accordance with the signal restrictions ahead to avoid an automatic brake application and the resulting penalty requiring the train to be brought substantially to a stop, requires the engineer to acknowledge the first danger signal (the train speed having been automatically required to be restricted to a minimum of, for example, 15 miles per hour on passing a caution signal, due to initiation of HCS) and perform a similar acknowledging act at repeated intervals of distances so long as the train is traveling in danger or caution territory. The penalty for failure of the engineer to manifest his vigilance, by performing the manual act called acknowledgment, also consists in requiring the train to be brought substantially to a stop. The mechanism provided to carry out this manifestation of his vigilance not only protects the train in case the engineer is dead or incapacitated, but also protects the train in the event

that he is asleep and does not notice either the wayside signals or the acknowledging signal lamp 62 located in the cab, so that the system is one that stimulates the engineer's vigilance and wakefulness.

Having thus shown and described only one simple type of automatic train control system to which the present invention has been applied, and having illustrated rather specific mechanism for carrying out the functions of a system embodying the present invention, it is desired to be understood that this has been done for the purpose of illustrating the invention rather than showing the scope of the invention or the particular mechanism preferably employed in practice, since, for instance, the same general arrangement of requiring acknowledgment by the distance interval may be applied to either intermittent or three-position continuous inductive type train control systems by making suitable additions and changes to adapt the invention to such systems, and all without departing from the scope of the invention or the idea of means underlying the same.

What is claimed as new and desired to be secured by Letters Patent is:—

1. In an automatic train control system, the combination of a speed restricting device governed in accordance with traffic conditions ahead and initiated if traffic conditions ahead are dangerous so as to gradually reduce the permissive speed at which the vehicle may travel without incurring an automatic brake application, means for applying the brakes regardless of any substantial speed at which the train is traveling and effective a predetermined distance after said speed restricting device has been initiated, and means for preventing said last mentioned means from applying the brakes effective if actuated at repeated distance intervals.

2. In an automatic train control system, the combination of a brake setting appliance, means requiring the engineer to manifest his vigilance upon the approach of his train to a signal set at danger and thereafter at repeated distance intervals by actuating a manually operable device so long as the train is in danger territory regardless of the train speed, provided it be above a predetermined minimum, and means for actuating said brake setting appliance to effect a brake application if the engineer fails to actuate said manually operable device when required, and if the engineer maintains said device operated for more than a predetermined distance interval.

3. An automatic train control system comprising, a brake setting appliance, means for rendering said appliance active including a permissive speed device and an actual speed device and effective if the actual speed exceeds the permissive speed, and other means for rendering said appliance active includ-

ing means effective after the train has traveled a predetermined distance in dangerous territory unless a suitable manually operable device operable independently of the train speed, is operated at repeated distance intervals of travel.

4. An automatic train control system comprising, a normally energized stick electro-responsive device which is de-energized effects an automatic brake application; two independent means for maintaining said device energized, one of which is effective so long as the train is traveling in clear territory and a predetermined distance in danger territory, and the other of which is effective if a suitable manually operable device is operated at repeated distance intervals.

5. In an automatic train control system, vehicle-carried apparatus comprising a permissive speed means which applies the brakes of the train if the speed is excessive, means for initiating said permissive speed means under dangerous traffic conditions ahead for rendering it active after a given interval of vehicle travel from the point initiated to impose a minimum speed restriction, distance governed means for successively actuating a cab signal and a device for imposing an automatic brake application regardless of speed above a predetermined minimum after a given distance of vehicle travel from the point at which said minimum speed restriction was imposed, and means including a manually operable member for preventing the automatic brake application regardless of speed provided said manually operable member is operated at predetermined successive intervals of vehicle travel from the point at which said minimum speed restriction was initiated.

6. In an automatic train control system, the combination of a shaft normally assuming its biased inactive stationary position, normally inactive means governed in accordance with traffic conditions ahead which when active rotates said shaft from its biased position, and means governed by said shaft and effective if said shaft has rotated through a certain angle for permitting said shaft to return to its biased position and for again permitting the first mentioned means to rotate said shaft against its bias, whereby the cycle of operation of said shaft is repeated so long as said first mentioned means is in its active condition.

7. In an automatic train control system, the combination of a normally energized brake control device which if de-energized effects an automatic brake application, speed governed means for de-energizing said brake control device if the speed of the train is excessive, means for de-energizing said brake control device regardless of the speed of the train, provided it be above a predetermined minimum, effective under predetermined traffic conditions ahead, a manually operable

acknowledging device which if operated from its normal position prevents de-energization of said brake control device irrespective of the condition of said last mentioned means, and means controlled by said first mentioned means for de-energizing said brake control device if said acknowledging device is not returned to its normal position.

8. In an automatic train control system of the two position continuous inductive type, a car-carried control relay energized in response to current flowing in the usual track circuit ahead of the train under clear traffic conditions and de-energized under caution and danger traffic conditions, a normally energized brake control device energized by a stick circuit, speed controlled mechanism governed by said control relay for controlling said brake control device, means governed by said control relay for momentarily breaking the stick circuit of said brake control device at repeated intervals of distance and effective so long as said control relay is deenergized and regardless of the speed of the train, and normally inactive manually operable acknowledging means for shunting the break in said stick circuit effected by said last mentioned means.

9. In an automatic train control system of the two position continuous inductive type, a car-carried control relay energized in response to current flowing in the usual track circuit ahead of the train under clear traffic conditions and de-energized under caution and danger traffic conditions, a normally energized brake control device energized by a stick circuit, speed controlled mechanism governed by said control relay for controlling said brake control device, means governed by said control relay for momentarily breaking the stick circuit of said brake control device at repeated intervals of distance and effective so long as said control relay is deenergized and regardless of the speed of the train, normally inactive manually operable acknowledging means for energizing said brake control device in spite of the break in the stick circuit effected by said last mentioned means, and means for de-energizing said brake control device if said manually operable acknowledging means is not returned to its normal position after each operation thereof.

10. In an automatic train control system of the type in which influences corresponding to traffic conditions are continuously transmitted from the trackway to a moving vehicle, a brake setting appliance maintained inactive in response to said influences while the vehicle is traveling under favorable traffic conditions ahead, means requiring the engineer to manifest his vigilance when influences corresponding to unfavorable traffic conditions are first transmitted from the trackway and thereafter at repeated distance

intervals so long as unfavorable traffic conditions exist by actuating a manually operable device, and means for actuating said brake setting appliance if the engineer fails to actuate said manually operable device when required.

11. In an automatic train control system, the combination of a brake setting appliance, means driven in accordance with the progress of the vehicle for actuating said brake setting appliance at repeated distance intervals under unfavorable traffic conditions, and a manually operable device operable independently of the train speed acting to prevent the actuation of said brake setting appliance by said means if operated at repeated distance intervals.

12. In an automatic train control system, the combination of a brake setting appliance, means driven in accordance with the progress of the vehicle for actuating said brake setting appliance at repeated distance intervals under unfavorable traffic conditions, and a manually operable device acting to prevent the actuation of said brake setting appliance by said means if operated at repeated distance intervals, said manually operable device including means for actuating said brake setting appliance if said device is maintained operated for more than a predetermined distance interval.

13. In an automatic train control system, the combination of a normally energized brake control device which if de-energized effects an automatic brake application, speed governed means for de-energizing said brake control device if the speed of the train is excessive, rotary means driven in accordance with the progress of the vehicle for de-energizing said brake control device regardless of the speed of the train above a predetermined slow speed limit and effective under predetermined traffic conditions ahead, a manually operable acknowledging device which if operated from its normal position prevents de-energization of said brake control device irrespective of the condition of said rotary means, and means controlled by said first mentioned means for de-energizing said brake control device if said acknowledging means is not returned to its normal position.

14. In an automatic train control system, vehicle carried apparatus comprising a permissive speed means which applies the brakes of the train if the speed is excessive, means for initiating said permissive speed means under dangerous traffic conditions ahead for rendering it active after a given interval of vehicle travel from the point initiated to impose a minimum speed restriction, distance governed means for successively actuating a cab signal and a device for imposing an automatic brake application even though the speed of the vehicle is below said minimum speed after a given distance of vehicle travel

from the point at which said minimum speed restriction was imposed, said distance governed means comprising a shaft normally biased to an inactive position, normally inactive means initiated by said permissive speed means when said minimum speed restriction is imposed, and when initiated rotating said shaft from its inactive position in accordance with the progress of the vehicle, means governed by said shaft and effective if said shaft is rotated through a certain angle for permitting said shaft to return to its biased position and for again permitting the first mentioned means to rotate said shaft against its bias, whereby the cycle of operation of said shaft is repeated so long as said first mentioned means is in its active condition, and means including a manually operable member for preventing the automatic brake application regardless of speed above a predetermined low limit providing said manually operable member is operated at predetermined successive intervals of vehicle travel from the point at which said minimum speed restriction was initiated.

15. In an automatic train control system of the two position continuous inductive type, a car-carried control relay energized in response to current flowing in the usual track circuit ahead of the train under clear traffic conditions and de-energized under caution and danger traffic conditions, a normally energized brake control device energized by a stick circuit and adapted to apply the vehicle brakes when de-energized, speed control mechanism governed by said control relay for controlling the energization of said stick circuit, distance operated means governed by said control relay for momentarily breaking said stick circuit at repeated distance intervals and effective so long as said control relay is de-energized and regardless of the speed of the train, a normally inactive manually operable device acting when operated to 40 shunt the break in said stick circuit effected by said distance operated means, and means for breaking said stick circuit if said manually operable acknowledging device is maintained operated for more than a predetermined distance interval.

In testimony whereof I affix my signature.
WINTHROP K. HOWE.
